UNITED STATES PATENT OFFICE.

GEORGE O. DRAPER, OF HOPEDALE, MASSACHUSETTS, ASSIGNOR TO THE DRAPER COMPANY, OF SAME PLACE AND PORTLAND, MAINE.

SPINNING APPARATUS.

SPECIFICATION forming part of Letters Patent No. 656,954, dated August 28, 1900.

Application filed October 23, 1899. Serial No. 734,425. (No model.)

To all whom it may concern:

Be it known that I, GEORGE O. DRAPER, of Hopedale, county of Worcester, State of Massachusetts, have invented an Improvement 5 in Spinning Apparatus, of which the following description, in connection with the accompanying drawings, is a specification, like letters on the drawings representing like parts.

The function of the spindle in spinning apparatus is at present merely to effect rotation of the yarn carrier or bobbin, the rotary motion transmitted to the spindle being imparted to the yarn-carrier as the two are held in frictional engagement. Heretofore 10 the spindle has been considered a necessary feature of such apparatus, and the only important modification is that usually known as the "dead-spindle" type, in which a stationary upright is utilized to carry or form an 15 axial support for a revolving shell on which the yarn-carrier is placed. In the course of my experiments to simplify the construction and cheapen the cost of spinning apparatus, with due regard to efficiency, I have been led 20 to the conclusion that the yarn-carrier should be itself rotated directly upon an upright axial support, thereby doing away with the intermediate shell of the dead-spindle type, and thus eliminating entirely the spindle 25 itself, as now commonly designated. I have practically embodied my invention in a number of different constructions, to be made 30 the subject-matter of other applications, and herein I have shown a very simple form of spinning apparatus, the yarn-carrier fitting an axial support therefor with a running fit and being provided with a suitable groove for the reception of the usual driving-band. In this 35 as in other embodiments of my invention the 40 yarn-carrier is preferably treated with some suitable antifriction compound and the question of wear is one of relatively-small moment. Warp-bobbins rarely last with ordinary handling much longer than a year, and they are 45 on the spinning-frame but half of that time, and it has been proved that a wooden bearing properly treated with an antifriction composition can run at present spindle speed for more than a year without showing extreme 50 wear. The bearing parts of the yarn-carrier,

therefore, should last as long as does the present bobbin as commonly used.

Figure 1 in side elevation and partly in section represents spinning apparatus embodying one form of my invention. Fig. 2 55 is a partial left-hand elevation of the apparatus shown in Fig. 1; and Figs. 3, 4, and 5 are details showing the mode of placing the yarn-carrier in operative position and applying the driving-band. 60

Referring to Figs. 1 and 2, the cylindrical upright standard or axial support A for the yarn carrier or bobbin B is shown as fixedly mounted in a stand or foot A', adapted to be held on the usual spindle-rail in well-known 65 manner. The yarn-carrier B, of wood or other suitable and preferably fibrous material, has a longitudinal central bore b¹ therethrough of a size to embrace the standard A with a running fit either through the whole 70 length of the yarn-carrier or at the ends thereof, if desired. At its lower end the yarn-carrier is tapered, as at b, and immediately above and adjacent the tapered end an annular band-receiving groove b' is formed, the 75 walls of said groove flaring from their line of intersection. The stand A' is shown as provided with an upturned guide a, having an opening a' therein, through which the driving-band C passes, the depressions a² in the guide 80 supporting the band when applying the yarn-carrier. 85

I have shown in Figs. 3, 4, and 5 successive positions assumed by the yarn-carrier as it is pushed down along the upright support 85 A to enter the bight of the driving-band, the taper b acting to guide the band into the annular groove b', the elasticity of the band permitting such operation. If desirable, the operative may assist such operation by helping to guide the band with the fingers or with any suitable tool held in the hand. 90

It will be noticed that the lower portion of the yarn-carrier is somewhat larger in diameter than the main body portion b² thereof 95 to thus make an enlargement at b³, which serves to support the yarn mass and hold it in position on the carrier. This is not absolutely necessary, but conforms to the usual practice. 100

To position a yarn-carrier, a simple downward pressure thereon while the driving-band is guided, as shown in Figs. 3 and 4, is sufficient.

5 The tension of the driving-band serves to maintain the yarn-carrier in vertical position on its axial support, or a lateral projection, as a⁶, on the standard A and supported by a spring s (see dotted lines, Fig. 1) could be 10 used as a vertical support, while permitting a downward movement of the carrier when applying the band.

The yarn-carrier is impregnated along its bore with a suitable antifriction compound 15 by having its pores impregnated with hot wax or grease or with antifriction compounds of suitable composition which resist wear from the motion about the standard.

Inasmuch as the yarn-carrier is directly controlled by the driving-band and is guided throughout its length by the upright standard, it can be run at high speed without the vibration which a rigid spindle would show at the same speed.

25 My invention is not restricted to the precise construction and arrangements shown and described, as the same may be varied without departing from the spirit and scope of my invention.

30 Having fully described my invention, what I claim, and desire to secure by Letters Patent, is—

1. In yarn-spinning apparatus, a fixed standard, a removable yarn-carrier rotatable thereon, having a tapering lower end and an adjacent annular groove for the driving-band, and the driving-band to engage said groove and rotate the carrier and also sustain it vertically.

35 2. A yarn-carrier for spinning apparatus, having an integral whirl, and a tapering end below the whirl, and rotating means to en-

gage the whirl and also to sustain the carrier vertically.

3. An upright standard, a removable yarn-carrier adapted to be axially supported thereby and rotated thereon and having an annular groove for the driving-band, and a band-guide, the yarn-carrier being sustained vertically by the tension of the driving-band. 45

4. A cylindrical standard, a support therefor having an upturned band-guide, and a removable yarn-carrier adapted to be rotated on the standard and provided with an annular groove for the driving-band, the tension 50 of the band supporting the yarn-carrier vertically.

5. Spinning apparatus comprehending a fixed upright standard or axial support, a yarn-carrier rotatable thereon and having a 60 contained bearing to travel upon the standard, and rotating and vertically-supporting means for and applied directly to the yarn-carrier, said means also providing the vertical support for the latter.

6. Spinning apparatus comprehending a fixed standard or axial support, a supporting-stand therefor having a band-guide, and a yarn-carrier adapted to receive the yarn directly thereupon and to rotate directly on and 70 in engagement with the standard, said yarn-carrier containing bearings and having an integral band-receiving portion.

7. Spinning apparatus comprehending a 75 rotatable yarn-carrier, an axial support therefor, and rotating means to directly engage the yarn-carrier and also sustain it vertically.

In testimony whereof I have signed my name to this specification in the presence of two subscribing witnesses.

GEORGE O. DRAPER.
